UNITED STATES PATENT OFFICE.

ERWIN FALKENTHAL, OF BERLIN-DAHLEM, GERMANY.

SUPPORTING SURFACE FOR FLYING MACHINES, PARACHUTES, AND THE LIKE, RUDDER SURFACES AND PROTECTING SURFACES.

Application filed September 2, 1924, Serial No. 735,478, and in Germany February 24, 1922.

This invention relates to a special construction of the supporting planes for aeroplanes, kites, parachutes or the like.

According to the invention the supporting plane consists of a smooth supporting surface with permanently open small, closely arranged perforations, these perforations having smooth sharp edges and a distance between each other about equal with the 10 smallest diameter of a perforation, measured in the direction of this diameter.

By this structure various advantageous results are obtained. In the first place, the weight of the supporting plane is diminished, without at the same time diminishing the supporting ability. Thus neither the 15 lifting power and steering ability of an aeroplane nor its resistance to the air in gliding is diminished. Moreover, the air friction 20 on the plane surface is diminished by the perforations, as about half of the plane is composed of air.

For parachutes a slower fall is ensured by the reduction of weight.

25 The invention is based upon the observation that a smooth plate made as above described with punched perforations of the aforesaid character offers the same resistance to flowing air as an unperforated plate. 30 This result may be explained by the fact, proven by experiment, that the impinging air stream is dispersed before and behind the plate into a large number of separate 35 eddies, which completely dissipate the air stream; while at a short distance behind the plate, viz, beyond the eddy-zone, no air flow occurs that can be regarded as originating from the impinging air stream. The whole 40 energy of the air stream is therefore transmitted to the perforated surface, and the latter behaves practically as a closed or continuous surface.

45 It has further been ascertained that under some circumstances such a perforated surface has even more resistance to air or lifting power than a closed surface. This phenomenon is perceived when the solid surface elements or parts are of small absolute size or breadth, for example about 10 millimetres. The increase of the pressure effect 50 results from the fact that on the rear side of each small solid surface element between the perforations a suction effect occurs, and these numerous small suction effects add up 55 to a considerable collective effect, which sup-

plement the direct wind pressure. In the experiments such a plate must have greater weight for resisting the air stream, and when used as a supporting plane it can carry more weight than when the perforations are 60 of greater diameter.

For the efficacy of the above-mentioned eddies it seems desirable to take care that on the rear side or the upper side of the supporting plane there shall be no longitudinal 65 wind. This wind may be obviated by giving the front or leading edge of the supporting plane or wing a rounded form, such form having already been found to be advantageous in the case of the closed or continuous 70 surface supporting planes of aeroplanes. The form of the leading edge must be selected in such a way that it deflects the air stream impinging from the front somewhat upwards, so that on the upper side of the 75 supporting plane there will be a space in which the eddies can form undisturbed.

The perforations in the wing are limited to that part of the wing which does not form part of the rounded leading rim of the 80 wheel.

In the drawing—

Figure 1 illustrates an aeroplane without such details that are of no interest for this 85 invention.

Fig. 2 illustrates in cross section a wing consisting of one curved plane, and

Fig. 3 illustrates a hollow wing composed of two curved planes with a rounded leading 90 edge.

The supporting planes *a* of the aeroplane Fig. 1 are provided with slit-like perforations *b* of the kind described above. The slits are arranged in spaced rows arranged in parallel, the slits in each row being also 95 arranged parallel to those of another row, and have a distance apart equal to the width of a slit.

Figure 3 shows a hollow wing of drop-like cross-section, which shape is known per se, 100 and which consists of two curved planes *a*, *a'* united by a rounded leading edge *c*, both the planes *a* and *a'* so far as they lie behind the leading edge being provided with perforations *b* according to the invention. Alternatively, however, only the under plane *a'* 105 may be provided with perforations, the upper plane *a* being left solid and continuous.

The material for the supporting plane or wing may be of any desired kind. 110

In the case of the hollow wing according to Figure 3 it may be made, for example, of sheet aluminium, which is provided with punched holes of about 1 to 5 centimetres in diameter, which are at the same distance (1 to 5 centimetres) from one another.

Supporting planes may also be made of canvas. An advantageous method of manufacture consists in connecting together strips of linen by strings, the strings being about 2.5 to 3 centimetres wide and being arranged at similar distances from one another.

The supporting plane may however be made by weaving, for example in such a way that staggered interwoven square surfaces join one another at the edges, or that interwoven strips are connected with one another only by the warp threads, and so forth. In the latter cases the breadth of the solid surfaces and the distance between them may be substantially decreased. The groups of thread that are not interwoven are in this case, in comparison with the interwoven surfaces, to be regarded essentially as open perforations, as no perceptible air resistance occurs on the individual round threads.

It is, of course, to be understood that the surface of the plane is smooth, i. e. free of projections, such as hoods, cowls or other devices projecting either above or below the plane or wing, such as have been proposed with respect to large openings through the planes.

The openings according to my invention are small and numerous; they have sharp edges such as are formed in punching metal.

I claim—

1. In an aeroplane or the like, a smooth supporting wing with small, permanently open, closely arranged perforations therethrough, said perforations being substantially perpendicular to the wing and having smooth, sharp edges and having a distance between them about equal to the smallest diameter of a perforation measured in the direction of this diameter.

2. In an aeroplane or the like, a smooth wing having a continuous surface with permanently open, closely arranged small perforations therethrough, these perforations having smooth, sharp edges and the distance between them being about equal with the smallest diameter of a perforation measured in the direction of this diameter.

3. A supporting plane for aeroplanes or

the like, having permanently open, closely arranged, narrow slits therein arranged parallel to one another and having smooth sharp edges, the distance between each two slits being about equal to the width of a slit, and the parallel rows of slits being spaced by unperforated portions of material.

4. A supporting plane for aeroplanes consisting of a wing of uniform surfaced material with permanently open, closely arranged, small perforations therethrough, these perforations having smooth, sharp edges with the distance between them about equal to the smallest diameter of a perforation, the leading edge of the wing being bent over and free from perforations.

5. A supporting plane for aeroplanes, consisting of a hollow wing of solid material with drop-shaped cross-section, the under wing plane having small, permanently open, closely arranged perforations with smooth sharp edges, the distance between each two of said perforations being about equal with the smallest diameter of a perforation measured in the direction of this diameter.

6. A supporting plane for aeroplanes, consisting of a hollow wing of drop-shaped cross-section, both the upper and the under plane of the wing being provided with closely arranged small perforations right up to the fore, rounded edge of the wing, the said perforations having smooth, sharp edges and the distance between said perforations being about equal with the smallest diameter of a perforation.

7. An aeroplane wing having a covering presenting a smooth, generally uniform surface and having numerous small, closely arranged, sharp-edged open perforations extending through the covering, promoting the formation of eddies near the surface of the plane.

8. A supporting plane for aeroplanes or the like whose supporting surface has small, closely arranged permanently open perforations, said perforations being in the form of narrow slots arranged in rows, the distance apart of the slots in a row not exceeding the width of the slots, and the distance apart of the rows of slots not exceeding the length of the slots.

In testimony whereof I have signed my name to this specification.

ERWIN FALKENTHAL.
